UNITED STATES PATENT OFFICE

IVY B. ROBERTSON, OF CHARLOTTE, NORTH CAROLINA, ASSIGNOR OF ONE-HALF TO
F. M. GRESHAM, OF CHARLOTTE, NORTH CAROLINA

PUMP

Application filed May 22, 1931. Serial No. 539,348.

The device forming the subject matter of this application is a pumping mechanism of the kind disclosed in my prior Patent No. 744,618. One object of the invention is to improve the structure by using a single frame, at the top of the well, instead of employing two vertically spaced frames. Another object of the invention is to cut down the amount of piping required, by making the hollow piston rod serve as a part of the outlet for the water.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Figure 1 shows in vertical section, a device constructed in accordance with the invention, parts being in elevation;

Figures 2 and 3 are sections taken, respectively, on the lines 2-2 and 3-3 of Figure 1;

Figure 4 is a top plan of the frame;

Figures 5 and 6 are vertical sections taken, respectively, on the lines 5-5 and 6-6 of Figure 4.

The numeral 1 marks a well, at the upper end of which there is a foundation 2 carrying sills 3 on which is supported a single frame 4 embodying foot plates 5 connected on their lower sides by cross bars 6 and connected on their upper sides by cross bars 7 carrying upstanding bearing posts 8. Upwardly extended brackets 9 are located to one side of the cross bars 7 and are secured at 10 to lugs 11 on the foot plates 5. A main shaft 12, which is horizontally disposed, is journaled for rotation in the bearing posts 7. A short shaft 14 is journaled in lateral offsets 15 on the posts 8. A roller 16 is carried for rotation on the shaft 14 and is

disposed in the same horizontal plane with a pinion 17 secured to the shaft 12, and to one side of a gear wheel 18 secured to the main shaft 12, between the brackets 9, the gear wheel 18 meshing with a pinion 19 on a horizontal operating shaft 20 journaled in bearings 21 on the brackets 9. The shaft 20 is rotated by means of a crank 22. A drum 23 is secured to the shaft 12, outwardly of the cross bars 7. A downwardly extended flexible element 24 is wound about the drum 23 and carries any desired number of weights 25 it being possible to increase or decrease the weight, at the will of an operator.

A vertically movable rack bar 26 meshes with the pinion 17 and is held in mesh with the pinion by means of the roller 16. The lower end of the rack bar 26 is connected to the closed upper end of a hollow piston rod 27 provided with a coupling 28 having a lateral spout 29 to which is connected a flexible tube 30 located in the well 1 and connected at its outer end to a fixed outlet pipe 31.

The lower end of the hollow piston rod 27 is secured in an inverted, cup-shaped cap 32 forming part of a piston 33, there being a downwardly closing check valve 34 in the piston 33, at the lower end of the hollow piston rod 27.

The piston 33 is mounted for vertical reciprocation in a cylinder 35, having a check valve 36 at its lower end, the check valve being disposed at the upper end of a pipe 37 secured in the lower end of the cylinder 35. On the lower end of the pipe 37, there is a strainer 38, the upper portion of the strainer being imperforate, and the lower portion of the strainer being perforated. An upwardly opening check valve 39 is mounted in the strainer, and is located between the perforate and imperforate portions of the strainer, as Figure 1 will show.

The device comprises a hanger, including a pipe 40 having its lower end mounted in the upper head of the cylinder 35. The upper end of the pipe 40 is connected to a plate 41, joined by upwardly extended rods 42 with the frame 4. The rods 42 carry a hori-

zontal guide 43 in which the hollow piston rod 27 slides, and the coupling 28 is located between the guide 43 and the plate 41. If desired, a vent 44 may be formed in the upper end of the cylinder 35.

In practical operation, the operator rotates the shaft 20 by means of the crank 22, and rotation is imparted to the main shaft 12 through the instrumentality of the pinion 19 and the gear wheel 18. When rotation is imparted to the main shaft 12, as aforesaid, the drum 23 is rotated, the flexible element 24 being wound about the drum, and the weights being raised. By the rotation of the shaft 12, rotation is imparted to the pinion 17, and the rack bar 26 is raised, carrying with it the hollow piston rod 27 and the piston 33. Water enters the lower portion of the cylinder 35, by way of the pipe 37 and the strainer 38. The cylinder 35 now is full of water, below the piston 33. A faucet (not shown) at the outlet end of the pipe 31 being closed, the parts will remain in the condition stated, until the faucet 25 is opened. When the faucet is opened, the weights 25 and the flexible elements 24 rotate with the drum 23, and rotation is imparted to the main shaft 12. When the main shaft 12 is rotated, the pinion 17 forces 30 the rack bar 26, the hollow piston rod 27, and the piston 33 downwardly, the check valve 34 opening, and the check valve 36 being closed. Water will thereupon be forced upwardly through the hollow piston rod 27, the coupling 28, the spout 29, the tube 30, and the pipe 31, so long as the faucet is open, or until the supply of water in the cylinder 35, below the piston 33, is depleted. The flexible tube 30, of course, permits the 35 piston rod 27 to move upwardly and downwardly, and affords a simple but effective connection between the piston rod and the outlet pipe 31.

Although the operating shaft 20 has been shown as capable of being rotated by the crank 22, it will be understood that the shaft may be rotated electrically, or by any other power.

What is claimed is:

50. Actuating mechanism for a pump, comprising transversely-spaced foot plates having upstanding lugs, there being a space between the foot plates, cross bars joined integrally at their ends to the foot plates and 55 affording a permanent connection between the foot plates, the cross bars having upwardly projecting posts disposed between the foot plates, upwardly extended inner and outer brackets located on opposite sides 60 of the lugs, the inner bracket having lateral contacting support on one of the posts, securing elements connecting the ends of the brackets with the lugs, a main shaft journaled in the posts, a drum on one end of the main shaft, outwardly of the other post

and located above said space, a flexible element wound about the drum and extended downwardly through said space, a pinion secured to the main shaft, between the posts, a rack bar between the posts and extended downwardly through said space, the rack bar meshing with the pinion, a roller supported by and between the posts and engaging the outer edge of the rack bar, a gear wheel secured to the main shaft and located 70 between the brackets, an operating shaft journaled in the brackets, means for rotating the operating shaft, and a pinion secured to the operating shaft, between the brackets, and meshing with the gear wheel.

In testimony that I claim the foregoing as my own, I have hereto affixed my signature.

IVY B. ROBERTSON.
